(57) **CLAIM**

The ornamental design for a pipe mounted attachment bracket, as shown and described.

DESCRIPTION

FIG. 1: is a perspective view of a pipe mounted attachment bracket;

FIG. 2: is a front view of the pipe mounted attachment bracket of FIG. 1;

FIG. 3: is a top front view of the pipe mounted attachment bracket of FIG. 1;

FIG. 4: is a side view of the pipe mounted attachment bracket of FIG. 1; and,

FIG. 5 is a bottom view of the pipe mounted attachment bracket of FIG. 1.

The broken line showing of a pipe mounted attachment bracket is for the purpose of illustrating portions of the article and forms no part of the claimed design.

1 Claim, 5 Drawing Sheets
